UNITED STATES PATENT OFFICE.

GEORGE R. CORNWALL, OF RYE, NEW YORK, ASSIGNOR, BY MESNE ASSIGNMENTS, TO
JAMES G. COFFIN, TRUSTEE.

PAPER-SPLITTING MACHINE.

1,165,074.

Specification of Letters Patent. Patented Dec. 21, 1915.

Application filed November 21, 1907. Serial No. 403,224.

To all whom it may concern:

Be it known that I, GEORGE R. CORNWALL, a citizen of the United States, residing at Rye, in the county of Westchester and State 5 of New York, have invented new and useful Improvements in Paper-Splitting Machines, of which the following is a specification.

The invention relates to machines for splitting sheets of paper and has in view more especially, according to certain features of the invention, a machine for splitting sheets of paper having printed matter on both sides so that the matter on one side 10 and the matter on the other side may be used separately in preparing printing plates by actinic action through the paper or otherwise.

Objects of the invention are to provide 20 such a machine which will operate upon many various kinds of paper stock, which will split the sheets with great facility and accuracy and place them otherwise in condition for the purposes specified and desired; which controls the splitting of the sheet so that each sheet resulting from the splitting operation is of a uniform thickness in all parts, and so that the sheets resulting 25 from the splitting operation are each of the same thickness or one of the resulting sheets is thinner than the other; the machine giving the least thickness to the side of the original sheet that the operator may desire. These and other objects of the invention 30 will in part be obvious and will in part appear herein.

The invention consists in the novel parts, arrangements, combinations and improvements herein shown and described.

40 The accompanying drawings referred to herein and forming a part hereof, illustrate one embodiment of the invention, the same serving in connection with the description herein to explain the principles of the invention.

45 Of the drawings: Figure 1 is a plan view of a machine built in part in accordance with the principles of the invention; Fig. 2 is a corresponding front elevation; Fig. 3 is an end elevation; Fig. 4 a transverse central section; and Fig. 5 is a fragmentary sectional view, partly diagrammatic.

In the illustrated embodiment, means are provided for applying a pull to one side of

the sheet of paper which it is desired to split 55 and also means for applying a pull on the other side of the said sheet and according to certain features of the invention means are provided for determining the direction or angle of the pull. It will be understood 60 that with many kinds of paper stock this latter is important and desirable in order to get a uniform splitting of the sheet.

According to certain features of the invention, and as shown in the illustrated embodiment, the means for applying a pull to each side of the sheet comprises flexible members designed for attachment to the sides of the sheet to be split in connection with means for drawing the said flexible members apart. Each of said flexible members as they are drawn apart carries a portion of the attached sheet with it and thus effects the splitting. The form of means for drawing the said flexible members apart 65 shown in the present embodiment, comprises two cylinders, and the said cylinders are shown arranged for rotation so as to draw the said flexible members away from each other and at a uniform speed. 80

Other features are included in the invention and will be set forth in this specification.

Referring in detail to the embodiment illustrated in the accompanying drawings, 1 85 indicates a sheet of paper to be split, 2 represents a flexible member attached to one side of the said sheet and 3 a flexible member attached to the other side of the said sheet. One of said flexible members may 90 be attached to the sheet to be split over the entire extent or area of one side of the sheet, and the other flexible member may be similarly attached to the other side of the sheet, and such an arrangement is contemplated by the invention in certain of its aspects. As shown herein the flexible member 2 is connected to a cylinder 4 by suitable means such as a longitudinal slot 5 while the flexible member 3 is also connected to a cylinder 6 by a longitudinal slot 7. The said cylinders, and also other parts of the machine, are mounted in a suitable supporting frame, as will appear from the drawings. 100 105

Means are provided, as hereinbefore indicated, for determining the direction or angle of the pull exerted on the two sides of the

sheet, and according to certain features of the invention it is contemplated to make said means settable for various angles so that whatever kind of stock is being operated upon, the angle of pull may be predetermined or adjusted in such manner as to give the exact thickness for a stripped portion that may be desired. The form of the said means shown in the present embodiment 5 comprises a directive device which may be relatively movable with respect to certain other parts of the mechanism in order to determine the angle of pull. The said directive device, as shown herein, comprises a block 8 provided with a slot 9, through which the sheet to be split and the flexible members pass. In this embodiment the movement of the directive device is about a pivotal center, although it will be understood that other forms of movement may be used in connection with the particular form of directive device or with other forms of directive device. Accordingly the block 8 is shown in the drawings as pivotally mounted 10 upon the supporting frame of the machine at 10 (see Fig. 3 of the drawings). There are also provided devices for securing the block 8 at any angle to which it may be set or adjusted. Any suitable devices may be 15 employed for this purpose and the form thereof herein shown comprises a plate 11 attached to the block 8 and moving in close proximity to a slotted plate 12 mounted upon the frame of the machine and comprises also a device for clamping them firmly together. The said clamping device is shown as a thumb-bolt 13 rotatably carried in the plate 11 and passing through the slot 20 in the plate 12.

25 Suitable means for rotating the cylinders 4 and 6 are provided, the illustrated form thereof comprising a crank 14 fixed upon the shaft of one of the cylinders and intermeshing-gears 15, shown fixed upon the other ends of the cylinder shafts. It will be understood therefore that in this embodiment the cylinders 4 and 6 rotate at a uniform speed and in opposite directions. If desired, a suitable means for holding the said cylinders stationary, as for instance when the machine is being adjusted or when a sheet is being put in, may be provided and such means may be of any desired form. In the 30 illustrated embodiment a form thereof is shown comprising a pin 16 passing through an aperture in the frame of the machine and entering an aperture in one of the said cylinders.

35 The manner of operation of the mechanism herein described is as follows: A sheet of paper 1 has attached to its two sides the flexible members 2 and 3 and the said members are also attached to the cylinders 4 and 6. This may be done in any suitable way, 40 as by means of an aqueous adhesive. The

sheet 1 will be positioned and directed generally by means of the block 8 and its slot 9. When the crank 14 is rotated in the proper direction the cylinders 4 and 6 will rotate, winding up the flexible members 2 and 3 upon the said cylinders respectively, and as the said flexible members are drawn away from each other each will carry the side of the sheet of paper attached to it, thus splitting the sheet, substantially as is shown in Fig. 5 of the drawings. The thickness of the split sheet upon each side of the split can be very accurately adjusted or determined by the direction or angle of pull of the flexible members. The movable block 8 may be set for any angle of pull desired by a slight oscillation upon its pivots 10, and after a proper setting of the parts is secured, the thumb-bolt 13 may be used to clamp the block in position. It will be understood that the flexible members 2 and 3 will wind upon their respective cylinders carrying each its portion of the split sheet. The flexible members 2 and 3 may then be disengaged from their cylinders and each face of the sheet then separated from its respective flexible member and the split sheet will then be ready for use in preparing a printing plate or for other purposes, as desired.

From all the foregoing it will be understood that a machine has been provided which realizes the objects of invention and advantages herein set forth together with other objects and advantages.

The invention in its broader aspects is not limited to the particular construction shown, nor to any particular constructions by which it has been or may be carried into effect, as changes may be made therein without departing from the principles of the invention and without sacrificing its chief advantages.

What I do claim as my invention, and desire to secure by Letters Patent, is:

1. A machine for splitting sheets of paper including in combination means for applying a pull to one side of the sheet, means for applying a pull to the other side of the sheet, and means for determining the angle of pull.

2. A machine for splitting sheets of paper including in combination means for applying a pull to one side of the sheet, means for applying a pull to the other side of the sheet, and settable means for determining the angle of pull.

3. A machine for splitting sheets of paper including in combination a flexible member for attachment to one side of the sheet, a flexible member for attachment to the other side of the sheet, a support, means mounted on and movable relatively to said support comprising two members movable relatively to each other and comprising a device for attaching one of said flexible members to one of said movable members, a device for

- attaching the other of said flexible members to the other of said movable members, and means for drawing said flexible members apart to split the sheet.
4. A machine for splitting sheets of paper including in combination a flexible member for attachment to one side of the sheet to be split, a flexible member for attachment to the other side of the sheet to be split, means for drawing said flexible members away from each other, and means for determining the angle at which each of said flexible members is drawn.
5. A machine for splitting sheets of paper including in combination a flexible member for attachment to one side of the sheet to be split, a flexible member for attachment to the other side of the sheet to be split, means for drawing said flexible members away from each other, and a directive device movable for determining the angle of pull of the said flexible members.
6. A machine for splitting sheets of paper including in combination two cylinders, means for connecting one of said cylinders and one side of the sheet of paper, means for connecting the other cylinder and the other side of the sheet of paper, and means for rotating the said cylinders so as to draw the two sides of the sheet of paper away from each other and a mounting for said cylinders.
7. A machine for splitting sheets of paper including in combination two cylinders, connections between one of said cylinders and one side of the sheet of paper, connections between the other cylinder and the other side of the sheet of paper, a directive device for determining the angle of pull upon the sheet of paper, and driving means for the said cylinders so as to draw the two sides of the sheet of paper away from each other.
8. A machine for splitting sheets of paper including in combination two cylinders, means for attaching a flexible member to one of said cylinders, means for attaching a flexible member to the other of said cylinders, a flexible member for attachment to one of said cylinders and to one side of the sheet of paper, another flexible member for attachment to the other cylinder and to the other side of the sheet of paper, and means for rotating the said cylinders so as to wind the said flexible members upon said cylinders and thus draw the flexible members away from each other.
9. A machine for splitting sheets of paper including in combination two cylinders, a flexible member for attachment to one of said cylinders and to one side of the sheet of paper, another flexible member for attachment to the other cylinder and to the other side of the sheet of paper, a directive device movable into various positions so as to determine the angle of pull upon the sheet of paper, and means for driving the said cylinders so as to draw the said flexible members away from each other.
10. A machine for splitting sheets of paper including in combination two cylinders, means for connecting one of said cylinders and one side of the sheet of paper, means for connecting the other cylinder and the other side of the sheet of paper, and means for rotating the cylinders in opposite directions, thereby drawing the two surfaces of the sheet apart and winding them upon the two cylinders respectively, thereby splitting the sheet.
11. A machine for splitting sheets of paper including in combination a flexible member for attachment to one side of a sheet of paper throughout its area, a flexible member for attachment to the other side of the sheet throughout its area, a support, a plurality of members mounted thereon movable relatively to each other, and means for attaching one of said flexible members to one of said movable members, means for attaching the other flexible member to the other of said movable members, and means for drawing said members apart at the same speed, so as to split the sheet, one part of the sheet going with the flexible member to which it is attached and the other part of the sheet going with the flexible member to which it is attached, thereby splitting the sheet.
12. A machine for splitting sheets of paper including in combination a flexible member for attachment to one side of a sheet of paper throughout its area, a flexible member for attachment to the other side of the sheet throughout its area, two cylinders, means for attaching one of the aforesaid members to one cylinder, means for attaching the other of said members to the other cylinder, and means for rotating said cylinders at the same speed so as to wind each flexible member with its portion of the split sheet upon the cylinder to which the said flexible member is attached, thereby splitting the sheet.
13. A machine for splitting sheets of paper including in combination a flexible member for attachment to one side of a sheet of paper, a flexible member for attachment to the other side of the sheet of paper, a movable directive device for the sheet of paper, and means for holding said directive device in any position to which it may be set.
14. A machine for splitting sheets of paper including in combination a flexible member for attachment to one side of the sheet to be split, a flexible member for attachment to the other side of the sheet to be split, a support, two members on said support movable toward and from each other, means for attaching one of said flex-

ible members to one of said movable members, means for attaching the other of said flexible members to the other of said movable members, and means for moving said 5 movable members away from each other to draw said flexible members apart to split the sheet.

15. A machine for splitting sheets of paper including in combination a support, 10 means mounted on said support for attachment to one side of the sheet of paper, means mounted on said support for attachment to the other side of the sheet of paper, and winding means for each of said attached

15 means, whereby the sheet is split and one of the split parts of the sheet wound with one of said attached means and the other split part of the sheet wound with the other of said attached means.

20. 16. A machine for splitting sheets of paper including in combination a sheet adapted to be attached to one side of the sheet to be split, a sheet adapted to be attached to the other side of the sheet to be

25 split, a support, a windable member mounted on said support and having means for engaging one of said sheets adapted to be attached to the sheet to be split, another windable member on said support and having means for engaging the other sheet adapted to be attached to the sheet to be split, and actuating means for said windable members.

17. A machine for splitting sheets of 35 paper including in combination a supporting frame, a pair of cylinders journaled therein, means whereby a flexible sheet may be detachably attached to each of said cylinders, two flexible sheets, said flexible 40 sheets being attached one to one side of the sheet to be split and the other flexible sheet being attached to the other side of the sheet to be split, and means for rotating said cylinders at the same speed.

45. 18. A machine for splitting sheets of paper including in combination a supporting frame, a pair of cylinders mounted in stationary bearings in said frame and rotatable together in opposite directions, two 50 flexible sheets adapted to be attached to the opposite surfaces of the sheet of paper to be split, means for attaching said flexible sheets to said cylinders, and means for rotating said cylinders.

19. A machine for splitting sheets of 55 paper including in combination a supporting frame, a pair of cylinders mounted in stationary bearings in said frame and rotatable together in opposite directions, two flexible sheets adapted to be attached to the 60 opposite surfaces of the sheet of paper to be split, means for attaching said flexible sheets to said cylinders along or parallel to the adjacent edge of the sheet to be split, and means for rotating said cylinders 65 whereby as the sheet is split the line of cleavage is substantially parallel to the end of the sheet.

20. A machine for splitting sheets of 70 paper, including in combination a flexible member for attachment to one side of a sheet of paper, a flexible member for attachment to the other side of said sheet of paper, a support and two members mounted upon said support and adapted to draw said flexible 75 members apart with a uniform tension throughout and means for causing relative movement of said two members.

21. A machine for splitting sheets of 80 paper, including in combination a flexible member for attachment to one side of a sheet of paper; a flexible member for attachment to the other side of said sheet of paper, a support and two moving members mounted in parallelism upon said support for 85 drawing said flexible members apart to split the attached sheet and means for effecting relative movement between said two members.

22. A machine for splitting sheets of 90 paper, including in combination a flexible member for attachment to one side of a sheet of paper, a flexible member for attachment to the other side of said sheet of paper, a support and two cylinders, rotatably 95 mounted in parallelism upon said support and means for winding one flexible member upon one cylinder and for winding the other flexible member upon the other cylinder to split the sheet and means for rotating said 100 cylinders.

In testimony whereof, I have signed my name to this specification, in the presence of two subscribing witnesses.

GEORGE R. CORNWALL.
